METHOD OF AND MEANS FOR INSTALLING A COUNTERFLASHING IN A WALL

Edward T. Berg, San Francisco, Calif.

Application March 4, 1957, Serial No. 643,795

1 Claim. (Cl. 72—127)

The present invention relates to the installation of counterflashings, such as are used to prevent seepage of water along vertical or inclined walls into the space underneath roofing materials that partially cover these walls. To hold such counterflashings in their proper position, it is necessary to provide retaining channels known as "reglets" in these walls.

It is an object of my invention to provide a simple, time-saving and inexpensive method of building a reglet into a wall during the construction thereof.

Another object of my invention is to provide a simple and inexpensive reglet that may readily be built into a wall during the construction thereof and which may be securely anchored within the wall to resist accidental dislocation or removal thereof.

When counterflashings are engaged in reglets, the space above and below the engaged portion of the counterflashing within the reglet should usually be filled with a plastic compound so that no moisture can penetrate into, and collect within, the reglet where it might cause corrosion of the reglet or the counterflashing and ultimately seep into the space underneath the counterflashing. To apply a moisture-excluding compound to reglets built into walls when the counterflashings are engaged therein, is a difficult, time-consuming and arduous task that requires considerable skill.

It is an object of my invention to furnish a simple and time-saving method of providing a moisture-excluding compound around the reglet-engaging portion of counterflashings.

These and other objects of my invention will be apparent from the following description of the accompanying drawing which illustrates certain preferred embodiments thereof and wherein

Figure 1 is a fragmentary perspective of a reglet embodying my invention before it is installed in a wall;

Figure 2 is a vertical section through a partially constructed wall to which a reglet embodying my invention is applied;

Figure 3 is a fragmentary section through a completed wall, with the reglet of my invention installed therein and with a counterflashing engaged within the reglet; and

Figure 4 is a vertical section through a wall, similar to Figure 3, illustrating a modified embodiment of my invention.

Previously, when counterflashings were anchored in vertical walls, it was customary to first complete construction of the wall, remove material from the side of the wall to form a longitudinal recess therein, insert a laterally bent flange at the upper end of the counterflashing into the recess, apply a moisture-excluding compound into the space above the engaged flange, and secure the flange in position by means of leaden wedges. To remove material from a finished wall so as to form a recess therein extending the full length of the wall, is difficult and time-consuming and it will usually yield a recess that is of non-uniform and irregular depth and

2

height. To introduce a plastic moisture-excluding compound into a recess above the engaged flange of the counterflashing is likewise a difficult and time-consuming task that requires many man-hours and which makes it often necessary for the craftsman to work in a kneeling or crouched position depending upon the location of the recess. Also, direct contact of the counterflashing in the recess with the material from which the wall is constructed, such as concrete or concrete bricks, causes frequently premature corrosion and resultant deterioration of the counterflashing.

In accordance with my invention I overcome all these difficulties and disadvantages by building a reglet into the wall during the construction thereof. In particular, I build the wall up to the desired level where the reglet is to be located, and place a reglet of a particular conformation upon the temporary top surface of the wall. This reglet is so constructed that it has no top or roof portion, and to this reglet I apply the moisture-excluding compound in the form of a long strip, and then complete construction of the wall above said strip to the desired level. In this manner I reduce the time normally required for filling the counterflashing-receiving recess in the wall with a moisture-excluding compound to a matter of minutes, and I have the assurance that every corner of said recess is completely filled with the compound.

In addition I construct the reglet of my invention in such a manner that it is securely anchored within the finished wall and cannot accidentally be dislocated or removed. Furthermore, I construct the reglet of my invention in such a manner that direct contact between the reglet and the counterflashing is held at a minimum, and that there is assurance that a layer of the moisture-excluding compound is not only located above the engaged flange of the counterflashing, but also below said flange in the space between the floor of the reglet and the counterflashing flange.

Having first reference to Figure 1, the reglet of my invention, collectively identified by the reference numeral 10, is formed by a sheet of metal, such as galvanized steel, copper, or zinc, and comprises a horizontal floor or base portion 12 which has an upwardly turned flange 14 along its rear edge and a downwardly turned lip 16 along its front edge. The base portion 12 contains a number of longitudinally extending ribs, as shown at 18 and 20. The reglet also comprises a thick strip 22 of a heavy plastic moisture-excluding material, such as calking compound, that is of roughly rectangular cross section and which is placed upon the ribs 18 and 20 and extends along the full horizontal length of the base or floor portion 12 with its outer side face 24 about flush with the lip 16 of the reglet. This strip of plastic compound is pressed down upon the ribs 18 and 20 until it fills the space between said ribs and extends into the space behind the rib 18, as shown in Figure 2, and in this condition its height should be such that its top surface is about flush with the top edge of flange 14. Its width, however, is appreciably shorter than the width of the base portion 12 of the reglet, so that there remains a substantial space 25 between the inner side 26 of the strip 22 and the rear flange 14 of the reglet 10 for reasons that will presently appear (Figure 2).

When a wall 30 has been built up to the level where the upper end of the counterflashing is to be secured to the finished wall, the reglet 10 is placed upon the top surface 32 of the partially completed wall in such a manner that its lip 16 bears against the front surface 34 thereof. With the reglet in the described position and a strip of a suitable moisture-excluding compound resting thereon in the manner illustrated in Figure 2, the craftsman continues building the wall by placing mortar into the space behind the rear flange 14 of the reglet and by introducing mortar

into the space between the outwardly directed face of the said flange and the rear side 26 of the strip 22. He then places bricks and mortar upon the top surface 36 of the plastic strip 22 pressing them down upon said strip so that their bottom surfaces are level with the top edge of the rear flange 14 of the reglet 10 as illustrated in Figure 3. Thus the plastic strip fills every corner of the reglet, except for the barrier of mortar 37 adjacent the outwardly directed face of the reglet flange 14. Thereupon the craftsman continues construction of the wall 30 in the normal manner until it has reached its desired height. The finished wall is then provided with a slot or recess that is completely filled with a moisture-excluding compound, which cannot be removed because it has flown around and into the space between the ribs 18 and 20 in the floor of the reglet. It is now an easy matter to introduce the laterally turned top flange 38 of a counterflashing 40 into the compound filled space and secure it in its proper position by means of suitable wedges of lead or like metal, as shown at 41 in Figure 3. Due to the presence of the ribs 18 and 20 in the floor of the reglet and owing to the manner in which the strip of plastic compound was pressed down upon the floor of the reglet, prior to completion of the wall, there is assurance that not only the space above the flange 38 of counterflashing 40, but also the space between said flange and the floor 12 of the reglet is completely filled with the moisture-excluding compound, so that there is no possibility for moisture to reach the area below the external portions of the counterflashing 40. The ribs 18 and 20 make it also impossible for the strip of moisture-excluding compound to be accidentally withdrawn from the recess in the wall, if it should become necessary to withdraw the counterflashing for the purpose of replacement; and the reglet itself cannot be torn out of the recess in the wall during replacement of the counterflashing because of the concrete barrier 37 that reaches into the space before its rear flange 14.

The embodiment of the invention illustrated in Figure 4 has all the advantages of the embodiment illustrated in Figure 3, but differs from said last mentioned embodiment insofar as it does not require any wedges for securing the counterflashing in position. Adjacent its recess-engaging flange 38', the counterflashing 40' of the embodiment of the invention illustrated in Figure 4, has a downwardly turned, smoothly curved portion 42 that conforms with the outer surface of the downwardly bent lip

16 of the reglet 10, and which overlies said lip when the flange 38' of the counterflashing is properly engaged in the compound-filled recess of wall 30. By securing the portion 42 of the counterflashing 40' to the lip 16 of the reglet 10 with the aid of a number of short screws 44 that reach into the wall 30, the counterflashing 40' may be safely secured in position without wedges, such as shown at 38 in Figure 3.

My method of, and means for, installing a counterflashing in a wall provide a very substantial saving in labor, time, and expense, and they result in an effective, neat, and dependable installation.

While I have explained my invention with the aid of certain preferred embodiments thereof, it will be understood that my invention is not limited to the specific constructional details shown and described, which may be departed from without departing from the spirit and scope of my invention.

I claim:

20 The method of constructing a recess for the reception of a counterflashing into a wall at a predetermined level during the construction of the wall, which comprises building the wall up to said predetermined level, placing a reglet having an elongated flat floor portion and an up-turned flange provided along the rear edge of said floor portion, with its floor portion upon the temporary top surface of the wall, placing an elongated strip of a plastic moisture-excluding material upon the floor portion of said reglet in such a manner that a space is left between the rear side of said strip and the flange of said floor portion, filling mortar into the space between the rear side of said strip and said flange, and continuing the construction of the wall behind said flange and above said strip to the desired height.
